UNITED STATES PATENT OFFICE.

WILBUR ALSON HENDRYX, OF DENVER, COLORADO.

PROCESS OF SEPARATING SOLIDS FROM LIQUIDS.

960,547.

Specification of Letters Patent. Patented June 7, 1910.

Application filed June 14, 1909. Serial No. 502,168.

To all whom it may concern:

Be it known that I, WILBUR ALSON HENDRYX, a citizen of the United States, residing at Denver, in the county of Denver and State of Colorado, have invented certain new and useful Improvements in Processes of Separating Solids from Liquids, of which the following is a specification.

My invention relates particularly to a process for the treatment of ores with cyanid or other solutions, and broadly to a process for separating solids from the liquids in which they may be suspended or with which they are associated.

For a full understanding of my invention reference is made to the accompanying drawing, wherein the figure is a central vertical sectional view of a preferred form of the device.

Referring to the drawing, 1 indicates a round tank having a converging bottom. For the purposes of this device the tank may be round, or square, or rectangular or of any desired shape. An inverted frustum 25 of a cone or pyramid may be used with good results.

Extending across the top of the tank are beams 3, 4, and secured to these beams are straps 5, 6, which carry a centrally arranged filling tube 2. Surrounding this tube 2 are a number of filter cells 8, which may be radially arranged if the tank is circular in form, these filter cells being supported by an annular ring 13, which is hung by rods 7 from the beams 3, 4. Inlet pipes 9, connected to the supply main 10, and outlet pipes 11, for the cells pass through and are secured to the walls of the tank, these pipes affording additional support for the filter cells.

12, 12 are valves for the outlet pipes 11.

I prefer to use filter cells of the kind shown in my Patent No. 885,047, granted April 21, 1908, and the representation here 45 is accordingly more or less diagrammatic.

17, 17, are decanting cocks arranged at suitable heights on the tank.

35 is a deflecting cone or plate secured to the tube 2, and is designed to break the force 50 of the stream of pulp as it is run into the tank. The tank itself is supported on a series of posts or standards 18, and extending downwardly from the circular or prismatic body-portion of the tank is a converging 55 hopper 40. Secured to the open end of the

hopper by a flange 36 is an L-shaped tube 19. A shaft 20, mounted in bearings 21, passes through a stuffing-box 24 into the horizontal portion of the tube 19. This shaft 20 is driven by a suitably operated 60 sprocket-wheel 22, and has thrust collars 23 to prevent longitudinal movement. Within the tube 19, the shaft has secured to it a series of propeller blades 25, spaced apart by spacing rings 26, which blades may be 65 considered as continuations of the conveyer screw 27, also secured to the shaft 20. These blades and the screw may be fastened to the shaft in any desired manner, as by squaring the shaft and providing the hubs which 70 carry the blades and screw with a similarly shaped opening. A set collar or nut 28 is fitted on the squared end of the shaft. Passing through slots in the bottom of the tube 19 are ribs or flukes 34, extending upwardly between the blades 25, for the purpose of preventing rotation of the mass of pulp or tailings as it is being delivered 75 through the tube 19.

Secured to the end of the tube is a valve 80 mechanism comprising a curved valve-plate 29; arranged to slide on a correspondingly curved guide plate 30, the valve plate 29 being held up to its seat by a spring 32 in the head 31, which is mounted on pivots 39 85 secured to the pipe 19. 33 is a suitable handle for operating the valve.

The manner in which my invention is operated depends upon the class of material to be handled. It is useful in metallurgical 90 plants such as concentrating mills, cyanid mills, and in the filtration of solutions in treatment of ores. The flow of water and crushed ore, as in concentration plants may go continuously to this machine, in which 95 case the water is taken off through the decanting cocks 17 or filter cells 8 while the thickened solids are removed by the mechanism at the bottom of the tank. In this case the water is returned for re-use. In 100 cyanid mills my invention may be used to separate the water from the refuse pulp or tailings in order to save the water or solution for re-use or for the valuable chemicals in the solution, or it may be used to dewater 105 the tailings in order to stack them, thereby keeping the same out of creeks whose waters are used for irrigation or domestic purposes. Poisonous chemicals, such as cyanid, are kept out of rivers and creeks, thereby pre- 110

venting the destruction of horses, cattle, fish and other animals.

One manner of operation of my invention in cyanid mills is as follows: Crushed ore 5 together with water or solution is run into the tank through the tube 2. The ore is allowed to settle in the bottom of the tank while the liquid rises and passes off through the decanting cocks 17 or filter cells 8, a 10 considerable amount of settled solids being kept in the tank in the space beneath the cells to prevent the water or solids from running out. As soon as the tank contains sufficient settled solids the valve 29 is 15 opened and the shaft 20 revolved slowly. The revolving sections of a screw 25 convey the solids onto the screw 27. The ribs or flukes guide the pulp and keep it from revolving around with the sections. The 20 screw 27 conveys the pulp on out through the discharge valve 38. As the solids settle in the converging bottom of the tank they become more and more compacted and action 25 of the propeller blades 25, ribs 34, and screw 27 in forcing the pulp through the partially opened valve, is to squeeze the moisture out of the solids and back up into the tank. This feature of preserving and recovering 30 the liquids, while delivering the solids practically dewatered, is of particular importance in the treatment of materials in which the liquids may themselves be valuable or contain valuable ingredients. The density 35 of the pulp when discharged can be further regulated by opening the valve 29 to a greater or less extent. When opened to its full extent, it permits free passage of the material, while a smaller opening causes the pulp or tailings to be more closely compacted. The discharged solids thus obtained 40 can be conveyed away on a conveyer belt or in a car.

If the water or solution is clear enough it may be decanted off over the top of the 45 tank or through the decanting cocks 17, the filter cells being omitted.

While I have shown the sections of a screw 25, ribs 34, and screw 27, I may use one continuous screw or several propellers 50 attached to the shaft, the purpose of this mechanism being to convey the settled solids out of the tank while at the same time conveying the same under pressure, thereby discharging pulp containing a low percentage 55 of moisture.

In some instances, it may be necessary to lubricate the solids as they are being delivered through the tube 19. For this purpose I provide a valved-pipe 50, through 60 which water, in small quantities, may be introduced.

While I have shown a gate or valve at the delivery end of the tube 19 in order to regulate or control the pressure which the 65 screw may exert to compact the solids, other

means capable of exerting a restraining effect on the material issuing from such tube, may be used.

I claim:

1. The process of separating solids from liquids, which consists in permitting the solids to settle beneath the liquid, while so submerged expressing liquid from such settled solids, and returning the expressed liquid to the main body of liquid. 70

2. The process of separating solids from liquids, which consists in permitting the solids to settle beneath the liquid, while so submerged expressing liquid from such settled solids, returning the expressed liquid to 80 the main body of liquid and simultaneously discharging the solids from which the liquid has been expressed.

3. The process of separating solids from liquids, which consists in collecting the solids beneath a body of liquid, and subjecting the solids while so submerged to continuously applied pressure to express liquid therefrom. 85

4. The process of separating solids from liquids, which consists in collecting the solids beneath a body of liquid, subjecting the solids while so submerged to continuously applied pressure to express liquid therefrom, and simultaneously discharging the material from which the liquid has been expressed. 90

5. The process of separating solids from liquids, which consists in collecting the solids beneath a body of liquid, subjecting the solids while so submerged to pressure to express liquid therefrom, and permitting the 100 expressed liquid to flow back through the uncompressed solid.

6. The process of separating solids from liquids, which consists in collecting the solids beneath a body of liquid, removing the 105 supernatant liquid by filtration, and subjecting the solids while so submerged to pressure to express liquid therefrom. 110

7. The process of separating solids from liquids, which consists in collecting the solids beneath a body of liquid, removing the supernatant liquid by filtration, subjecting the solids while so submerged to pressure to express liquid therefrom, and permitting the 115 expressed liquid to flow back through the uncompressed solid.

8. The process of cyaniding ores, which consists in agitating the ore in a cyanid solution, permitting the ore to settle beneath the solution, while so submerged expressing the solution from the ore, and returning the expressed solution to the main body of solution. 120

9. The process of cyaniding ores, which consists in agitating the ore in a cyanid solution, permitting the ore to settle beneath the solution, while so submerged expressing the solution from the ore, and permitting the expressed solution to flow back through the 125 uncompressed ore.

130

10. The process of separating solids from liquids, which consists in collecting the solids beneath a body of liquid, subjecting the solids while so submerged to pressure to express liquid therefrom, returning the expressed liquid to the main body of liquid and removing the supernatant liquid.
- 5 11. The process of separating solids from liquids, which consists in collecting the solids beneath a body of liquid, subjecting the solids while so submerged to pressure to express liquid therefrom, returning the expressed liquid to the main body of liquid and removing the supernatant liquid by filtration.
- 10 12. The process of separating solids from liquids, which consists in collecting the solids beneath a body of liquid, subjecting the solids while so submerged to continuously applied pressure to express liquid therefrom, returning the expressed liquid to the main body of liquid and removing the supernatant liquid.
- 15
- applied pressure to express liquid therefrom, returning the expressed liquid to the main body of liquid and removing the supernatant liquid.
13. The process of separating solids from liquids, which consists in collecting the solids beneath a body of liquid, subjecting the solids while so submerged to continuously applied pressure to express liquid therefrom, returning the expressed liquid to the main body of liquid and removing the supernatant liquid by filtration.

In testimony whereof, I affix my signature in presence of two witnesses.
